ATTORNEY

UNITED STATES PATENT OFFICE

2,598,243

RAZOR

Alberto Estrada, Los Angeles, Calif.

Application March 16, 1946, Serial No. 654,968

1 Claim. (Cl. 30—59)

1

This invention relates to new and useful improvements in a shaving device, in which means for operating the same are enclosed within the handle and the head, and more particularly to such devices, where a shaving blade of conventional design is moved to and fro and with its cutting edge in direct contact with the skin.

With the above and other objects in view, this invention consists of the novel features of construction, combination, and arrangement, of parts, hereinafter fully described, claimed, and illustrated in the accompanying drawings, forming part of this specification, and in which similar characters of reference indicate corresponding parts in all views, and in which:

Figure 1 is a longitudinal section of my invention.

Figure 2 is a longitudinal section taken on line 2—2 of Figure 1.

Figure 3 is a transverse section taken on line 3—3 of Figure 1.

Figure 4 is an enlarged sectional view of a detail of my invention.

Figure 5 is a plan view of Figure 1 with the blade holding means removed.

Figure 6 is a perspective view of the blade holding means.

Referring now particularly to Figures 1, 2, and 3 my shaving device consists of a handle 10, which is secured to a hollow head 11, as shown at 12.

A spring 13 is housed within the handle 10, one end of this spring being attached at 14' to a knob 14 rotatably arranged within the handle 10. The knob 14 is provided with openings 15, which may be engaged by a spring prong 16 formed from the handle 10. The other end of the spring 13 is fastened at 17' to a disk 17, which is secured as at 18 to a hub 19 extending from a gear 20 and rotatably arranged within the head 11. As shown at 18, the disk 17 and hub 19 are also connected to a rod 21, which extends through the hub 19 and gear 20 into a pinion 22. As shown at 23 the rod 21 is formed with a shoulder to act as a spacer between the gear 20 and pinion 22.

A gear 24 and a pinion 25 are rotatably mounted in the housing 11, as shown at 26, and in a plate 27, as shown at 28. This plate 27 may be secured to the head 11 as by means of screws 29. Thus arranged the gear 20 is in mesh with the pinion 25 and through the gear 24 engages the pinion 22. A friction disk 30 may be brought into contact with the gear 24, said disk 30 ex-

tending into a threaded stem 31 through the head 11 and terminating into a knob 32.

The other end of the rod 21 extends through the knob 14 and is threaded as at 33 to receive a nut 34, thus longitudinally holding the knob 14 in place within the handle 10, but still allowing a free rotary movement of the knob 14.

As may be clearly seen now, when the friction disk 30 is brought in full contact with the gear 24, the spring 13 may be wound to any desired tension by means of the knob 14 and locked by the spring prong 16 and openings 15.

The pinion 22 extends into a hub 35 and through the plate 27 as shown at 36 in Figure 4. An eccentrically located bore is provided in the hub 35 and pinion 22 to accommodate a pin 37, the latter being normally held against the shoulder 38 by a spring 39.

The plate 27 carries the usual guards 40 and is provided with dovetails 41. Balls 42 may also be arranged in the plate 27, if so desired.

Referring now specifically to Figures 1, 2 and 6 a blade holding member 43 is formed from a lower plate 44 and an upper plate 45 which are hinged as at 46. The upper plate 45 is provided with a latch member 47 to engage a notched portion 48 on the lower plate 44 when in a locked position. The upper plate 45 also carries ribs 49 which in a locked position fit into grooves 50 in the lower plate 44. The latter also carries downwardly extending and inwardly bevelled lugs 51 to slidably fit over the dovetails 41 of the plate 27.

As may now clearly be seen that by means of the ribs 49 passing through the slot 52 of a conventional razor blade 53 and by the locking members 47 and 48, the blade 53 may securely be held in place between the lower plate 44 and the upper plate 45.

The blade holding member 43 may then be slidably mounted on the plate 27 by means of the lugs 51 and dovetails 41 until the pin 37 engages a slot 54 in the lower plate 44. The pin 37 may be depressed until the blade holding member 43 has cleared the latter.

As may be now fully understood from the foregoing description, that after releasing of the friction disk 30, wound up spring 13 will operate the gear 20, the pinion 25, the gear 24 and the pinion 22 and by means of the eccentrically rotating pin 37 engaging the slot 54, will cause a to and fro movement of the blade 53 and blade holding member 43.

To reduce friction the underside 55 of the lower plate 44 may engage the balls 42.

It is obvious that slight changes may be made in the form, construction and arrangement of the several parts, as shown, within the scope of the appended claim, without departing from the spirit of my invention, and I do not, therefore, wish to limit myself to the exact construction and arrangement shown and described herein.

What I claim as new, and desire to secure by Letters Patent of the United States, is:

In a device of the class described, a blade holding member comprising a lower and an upper plate hingedly connected, said lower plate having a notched portion, the upper plate being formed with a latch member adapted to engage the latter, the lower plate having grooves and ribs upon the upper plate adapted to engage said grooves, when said plates are in locked position, a plate provided with guards and being formed with dovetails, downwardly extending and in-

wardly bevelled lugs upon the aforesaid lower plate adapted to slidably fit over said dovetails.

ALBERTO ESTRADA.
